(57) **CLAIM**

I claim the ornamental design for a tool handle, as shown and described.

DESCRIPTION

FIG. 1 is an upper, left, front perspective view of a tool handle;

FIG. 2 is top plan view thereof;

FIG. 3 is a bottom plan view thereof;

FIG. 4 is a left side elevation view thereof;

FIG. 5 is a right side elevation view thereof;

FIG. 6 is a rear elevation view thereof;

FIG. 7 is a front elevation view thereof; and,

FIG. 8 is an upper, left, front perspective environmental use view.

In the drawings, the broken line showing of features of the tool handle illustrate portions of the tool handle that form no part of the claimed design; whereas, the broken line showing of the environmental use view depicts environmental subject matter and is provided for the purposes of illustrating environmental use structure and context and also forms no part of the claimed design.
